UNITED STATES PATENT OFFICE.

RALPH S. TWOGOOD, OF BERKELEY, CALIFORNIA.

HOUSEHOLD FURNACE.

Application filed September 11, 1922. Serial No. 587,400.

To all whom it may concern:

Be it known that I, RALPH S. Twogood, a citizen of the United States, residing at Berkeley, in the county of Alameda and 5 State of California, have invented certain new and useful Improvements in Household Furnaces, of which the following is a specification.

My invention relates to the class of furnaces which, especially intended for heating buildings, are appropriately termed 10 household furnaces.

One object of my invention is to provide a combination hot-air and hot-water or 15 steam furnace, thus making use of the advantages of both types of heating systems. Another object of my invention is to provide, in such a combination furnace, means for apportioning, at will, the heat derived 20 from the combustion of the fuel, between the air and water heating portions of the furnace. Still another object is to provide a furnace having the greatest possible thermal efficiency.

25 My combination furnace is particularly well adapted for use in such buildings as hotels, in which the parlors, dining rooms, and other public rooms, which must be kept warm continuously, are heated by hot air led directly from the furnace, while the more remote bed room are heated by steam or hot water controlled at will by the occupants. In such buildings also, by the use 30 of my furnace, a constant supply of steam is available in the kitchen, laundry, and other service rooms. My furnace may also be used in the same manner for heating residences, the halls, parlors, etc. being heated by hot air led directly from the furnace located 35 beneath these rooms, and the more remote bed rooms being heated by steam or hot water.

40 My furnace is so constructed that the hot gaseous products of combustion may be used first for heating the water for the hot water or steam system, and then a large portion of the heat remaining in the hot gases, which is ordinarily lost in a simple steam furnace, may be used for heating the air 45 for the hot air system. In this manner I am able to secure a very high thermal efficiency.

With these ends in view, my invention 50 consists in the novel furnace which I shall

now fully describe by reference to the accompanying drawings, wherein—

Fig. 1 is a partly broken front elevation of my furnace.

Fig. 2 is a vertical section of the same, taken on the line 2—2 of Fig. 3.

Fig. 3 is a transverse vertical section taken on the line 3—3 of Fig. 2.

Fig. 4 is a broken sectional plan of the air heating chamber, taken on the line 4—4 of Fig. 2.

Fig. 5 is a broken sectional plan of the side wall, taken on the line 5—5 of Fig. 2.

Fig. 6 is a perspective view of one of the removable side wall blocks.

Fig. 7 is a plan view of a portion of the deflector wall overlying the fire-box.

Fig. 8 is a section of the same, taken on the line 8—8 of Fig. 7.

Fig. 9 is a perspective view of a portion of the damper controlling means.

Fig. 10 is a vertical section of the fire-box, taken on the line 10—10 of Fig. 2.

Fig. 11 is a sectional detail showing the arrangement of the water drums when the furnace is adapted for hot water rather than steam heating.

In the drawings, the reference numeral 1 designates the outer shell or casing of my furnace, which is preferably made of brick or other similar material to prevent unnecessary radiation of heat.

Within the lower left-hand portion of the casing, as viewed in Figs. 1 and 2, is a fire box 2, constructed in any well known manner in accordance with the type of fuel which is to be used. Above the fire box is a flat horizontal baffle or deflector wall 3, Figs. 2 and 3, preferably constructed of refractory tile or fire brick, each brick 4 being provided upon opposite edges with semi-circular under-cut recesses 5, as shown in Figs. 7 and 8, so positioned that the two recesses of adjoining bricks form a cylindrical recess for the reception of the head of a bolt 6, these bolts passing through and being secured to horizontal supporting beams 7, Figs. 2, 3, 7 and 8. Thus when the bricks 4 are assembled, they form a continuous refractory baffle, thus protecting the supporting beams 7 and bolts 6 from the heat of the fire.

The deflector wall 3 extends far enough toward the right, away from the fire-box 2,

to insure complete combustion before the hot products of said combustion reach the relatively cool surfaces of the heating chambers, thus preventing an undue formation 5 of soot and smoke, with the consequent reduction of efficiency.

Beside the fire box 3 is the steam or water heating chamber 8, Figs. 2 and 3, in which are positioned a series of coils 9 of pipe or 10 tubing. The upper and lower ends, 10 and 11, respectively, of each coil 9 are preferably brought through the front wall of the casing 1, as shown in Fig. 3, and, if the furnace is intended for steam heating, are connected directly with a drum 12, which acts both as a water storage tank for supplying the coils 9 and as a receiver for the steam formed in said coils. A water supply pipe is shown at 13 and a steam line at 14, the latter leading to the radiators, not shown. If the furnace is designed for hot water heating, the drum 12 is connected only with the upper ends 10 of the coils 9, and a second drum 15 is provided and connected with the lower 20 coil ends 11, as shown in Fig. 11. In this construction the pipe 14 is the hot water line to the radiators, not shown, and the pipe 13 is the return line from said radiators. The drum 12 (and also the drum 15, if one is provided) and the exterior portions 10 and 11 of the coils 9 are preferably embedded in suitable insulating material 16, Figs. 1, 3 and 11.

The coil heating chamber 8 is provided 35 with a vertical baffle 17 extending downwardly from its top 18, as shown in Fig. 2. This baffle causes the hot gases from the fire box 2 to pass downward through the left-hand portion of said chamber 8, and upward 40 through its right-hand portion. A horizontal passage 19 is provided as a by-pass for the hot gases above said coil chamber 8. A damper 20, operable to close either the outlet 45 of said chamber 8 or the by-pass 19, may be adjusted to any desired position to apportion the hot gases between said chamber and said by-pass, thereby regulating the amount of heat imparted to the coils 9.

The hot gases rise from the damper 20 50 through a vertical passage 21, Fig. 2, at the right of the furnace; thence through a plurality of horizontal flues 22 located in the air heating chamber 23, thence into a vertical passage 24 at the left, and thence into the stack 25, the path of said hot gases being 55 shown by full line arrows. A suitable damper or check-draft 26 is preferably provided in said stack. Air enters the chamber 23 through an inlet 27, Fig. 3, at the rear, passes 60 up and around the heating flues 22, as shown by the dotted arrows, and is led off, in a heated condition, by pipes 28. On account of the horizontal position of the flues 22, and their staggered relation to each other, as 65 shown in Figs. 2 and 3, the greatest possible

circulation of air over the surfaces of said flues is secured. Said air, being impeded in its upward current by said horizontal staggered flues, is thoroughly mixed and evenly heated throughout its entire body, thus giving the maximum thermal efficiency per unit of heating surface.

The horizontal flues 22 are secured at their ends to heads 29 and 30, Figs. 2 and 4. One of these heads 29, is preferably a flat sheet, 75 and is set in grooves formed in the walls of the casing 1, as shown in Fig. 4, with suitable packing 31 to permit its lateral expansion and contraction.

The other head 30 is similarly mounted in 80 grooves in the casing walls, and is preferably provided with a flanged or bent edge projection 32, to allow for expansion and contraction of the flues 22. One side wall of the casing 1 is preferably provided with removable 85 interfitting blocks 33 of formed concrete or other suitable material, as shown in Figs. 1, 5 and 6, to provide access to the flues 22 for cleaning. A clean-out door 34, Figs. 1 and 2, is also provided in the opposite wall 90 for the same purpose.

In addition to the damper 20 and the check-draft 26 described above, there is provided the usual air-supply damper 35, Figs. 1 and 10, in the door of the ash-pit 36. These three dampers are respectively connected by cables or chains 37, Fig. 1, with vertical slidable and axially turnable rods 38 which extend through the floor 39 of the building and are provided with handles 40 above said floor and similar handles 41 below, whereby said rods 38 and the dampers connected therewith may be operated either from the furnace room or from the floor above. For retaining the dampers in any desired position I provide a plate 42, Figs. 1 and 9, having bearings 43 in which the rod 38 is both slidable and rotatable. Said plate is provided with spaced projecting pins 44, adapted to be engaged by a pin or lug 45 secured to the rod 38. Thus by rotating said rod, the lug 45 is freed from the pins 44, and said rod can be raised or lowered to adjust its connected damper to the desired point. A reverse rotation of the rod then locks said damper by engaging the lug 45 with one of the pins 44. For simplicity in Fig. 1 of the drawings, I have shown this retaining means as associated with only one of the rods 38, but it is to be understood that the same devices are applied to the other rods for the same purpose.

In addition to the manual control described above, the damper 35 is also automatically controlled by the pressure of the steam generated in the coils 9. To this end the cable 37 attached to said damper 35 is passed over a pulley 46, Fig. 1, mounted upon the adjustable rod 38, and the end of said cable is then secured to the lever 47

of a pressure controlled regulating device 48. Said regulating device may be of any well known form, and is connected by a pipe 49 with the steam drum 12. These parts 5 are so connected that any decrease in steam pressure will open the damper 35, thereby increasing the rate of combustion of the fire, and vice versa.

In the operation of my furnace, if the by-pass damper 20, Fig. 2, is set in a vertical 10 position, thereby closing the by-pass 19, all the hot gaseous products of combustion pass over the water coils 9, and then through the air heating flues 22. If more heat is desired 15 from the hot air system, the damper 20 is moved to open said by-pass 19 slightly, thereby allowing some of the hot gases to pass directly to the air heating flues 22. At the same time the automatic regulator 48 20 opens the damper 35 further, to increase the fire and keep the temperature of the steam constant. If no steam is required, the damper 20 can be set to by-pass all the hot gases to the air heating flues 22, and the 25 damper 35 regulated by hand.

I claim:—

1. A furnace comprising a shell; a fuel-burning member in the shell; a deflector wall for the products of combustion overlying said fuel burning member; an air-heating member within the shell overlying said deflector wall and exposed to the heat of the products of combustion passing around the end of the deflector wall, in their course 30 to their exit from the shell; a water-heating member at one side of the fuel burning member and exposed to the heat from the products of combustion passing under the deflector wall; and a damper disposed to 35 selectively include and exclude said water-heating member from the course of the products of combustion.

2. A furnace comprising a shell; a fuel-burning member in the shell; a deflector wall 40 for the products of combustion overlying said fuel burning member; an air-heating member within the shell overlying said deflector wall and exposed to the heat of the

products of combustion passing around the end of the deflector wall, in their course to 50 their exit from the shell; a water-heating member at one side of the fuel burning member and exposed to the heat from the products of combustion passing under the deflector wall; and a damper disposed to 55 selectively include and exclude said water-heating member from the course of the products of combustion, and proportion their volume between said air-heating and water-heating members. 60

3. A furnace comprising a shell; a fuel-burning member in the shell; a deflector wall for the products of combustion, overlying said fuel-burning member; an air heating member within the shell overlying 65 said deflector wall; and flues extending substantially horizontally through said air-heating member for receiving the products of combustion passing around the end of the deflector wall and conducting them 70 through said air heating member in their course to their exit from the shell.

4. A furnace comprising a shell; a fuel-burning member in the shell; a deflector wall for the products of combustion overlying said fuel-burning member; an air heating member within the shell overlying said deflector-wall; flues extending substantially horizontally through said air heating member for receiving the products of combustion 75 passing around the end of the deflector wall and conducting them through said air heating member in their course to their exit from the shell; a water-heating member at one side of the fuel burning member and exposed to the heat from the products of combustion 80 passing under the deflector wall; and a damper disposed to selectively include and exclude said water-heating member from the course of the products of combustion and 85 proportion their volume between said air-heating and water-heating members. 90

In testimony whereof I have signed my name to this specification.

RALPH S. TWOGOOD.
